UNITED STATES PATENT OFFICE

LEONARD R. CARLEY, OF WATERTOWN, AND WALTER T. ABEL, OF WATERVILLE, CONNECTICUT, ASSIGNORS TO THE PATENT BUTTON COMPANY, OF WATERBURY, CONNECTICUT, A CORPORATION OF CONNECTICUT

SHELL BUTTON

Application filed June 18, 1931. Serial No. 545,322.

Our invention relates to new and useful improvements in buttons, and more particularly to a button of the shell type in which there is securely fastened a vice or die into 5 which the fastener is to be driven to thereby hold the button tightly in place.

One of the principal objects of the invention is to produce a button of the shell type which will be extremely light in weight, in 10 that it is not necessary to provide an extra anvil to fill up the space between the rim of the button and its top or cap.

Still another object of the invention is to provide a button of the shell type in which 15 there is fastened a small die and which die, in turn, is tightly secured in place, so that when the button shell and die are being tumbled around in the hopper of an assembling machine there is no possibility of the die 20 dropping out of its shell.

Still another object of the invention is to produce a button wherein the die can be forced into the hub of the shell of the button up to its shoulder and will tightly remain in 25 position after being placed in the hub and the top of the die will act as a reinforcement for the top or cap of the button.

Still another object of the invention is to produce a button consisting of a shell, a small 30 die with the shoulder and a cap, and the button hub and die so indented that the die, after once being so acted on, will always remain properly and rigidly fixed within the hub of the shell.

With these and other objects in view, the 35 invention consists in certain new and novel arrangements and combination of parts, as will be hereinafter more fully described and pointed out in the claims.

Referring now to the drawings showing a 40 preferred embodiment,

Fig. 1 is an enlarged side elevation, bottom plan, and cross section of the little die;

Fig. 2 is an enlarged top plan view of the 45 button shell;

Fig. 3 is a sectional view thereof taken on the line 3-3 of Fig. 2;

Fig. 4 is a sectional view of the button shell with the die in place and diagrammatically showing the parts of the tool for indent-

ing the hub of the button head and the die to rigidly hold the die in place;

Fig. 5 is a sectional view of the assembled button and showing the tack to rigidly hold the button to the cloth.

55

Referring now more particularly to the several views, there is shown in Figs. 2 and 3 a button shell 1 comprising the hollow integral hub 2, the outwardly extending body portion 3 and the upwardly and outwardly flared rim 4. This shell is of the perforate 60 type, that is, the bottom is pierced, as at 5, this opening assisting in guiding the prong 6 of a tack fastener 7 into its final position, as will be shortly explained.

Referring now more particularly to Fig. 1, there is shown the small vice or die 8 which has a substantially vertical outer peripheral wall 9; a shoulder 10, and the integral top 11. The bottom surface 12 of the die is split radially, as at 13, and is indented or perforated, as at 14, the little jagged ends of metal 15 being clearly seen in the sectional view of Fig. 1. This little circular die is then driven within the hollow hub 2 of the shell, and it will be noticed that the height of the die from the shoulder 10 to and including the top 70 surface of its cover 11 is now flush with the upper peripheral edge of the rim 4 of the button.

When the die is jammed within the hub, as before mentioned, the two perforated bottom portions 5 and 14 are now in alignment and will appear as shown in Fig. 4.

To rigidly hold this die in place, so that 75 there is no possibility of its dropping out when tumbled around in the hopper of an assembling machine, the partly assembled button is placed in a vice (not shown), while oppositely extending punches 16 with the little points 17 thereon will be driven inwardly towards each other to indent the hub, as at 18, and also displace the metal, as at 19, in the little die, as may be clearly seen in Figs. 4 and 5.

It will be noticed that these little indentations are just directly below the surface of the body 3 of the button shell and are hardly perceptible to the eye, so that the button is in no way unsightly disfigured.

100

We have not shown the mechanism for forcing these little punches 16 inwardly, but it will be understood that the buttons will be automatically fed into a machine and these 5 buttons and hubs indented in a very rapid manner.

After the die has thus been rigidly fastened within the hub of the button shell, a cap 20 of usual form may be tightly crimped, as 10 at 21, over the outwardly flared rim 4 of the button. Of course, this button cap may have any desired insignia thereon or any fanciful design.

It will also be noticed that when the cap 15 20 is placed in position, the upper surface 11 of the die will act as a backing for the cap during its crimping operation and will also rigidly hold the cap in place during the life 20 of the button and prevent the cap from being forced or sagging inwardly.

When the buttons are attached, the button heads 1 will be placed in the ordinary button fastening machine and the button heads fed 25 from one hopper and the tacks from another hopper (not shown) and the prong 6 will be driven into the hub of the button shell and die and will be mutilated, as shown in Fig. 5, the upper surface 11 of the die turning the prong of the tack or fastener 30 and the button will thus be rigidly secured to the cloth 22, as shown in Fig. 5.

From the foregoing, it will be seen that we have produced a shell button which is extremely simple in construction and exceeding light in weight.

Finally, the little die will remain in its proper set position and will deflect the prong of the fastener when being attached to the cloth and rigidly support the cap, thus 40 saving the expense of an anvil and holding the button down to a minimum weight.

Having thus described our invention, what we claim and desire to secure by Letters Patent is:—

45 1. A button comprising a hollow shell, an integral hub, a die fitting within said hub, a cap over said shell and die, the metal of the hub of the button shell having small dents formed therein, and the metal displaced by said dents fitting within resultant dents in the die to thus rigidly hold the die 50 within the hub.

2. A button comprising a hollow shell and an integral hollow hub, a die fitting within 55 the hub, a shoulder on said die and overlying the peripheral upper edge of the hub, a cap on said button shell and resting on the upper surface of the die, the hub of the button shell being deformed at points and fitting within complementary deformations in the die to thus rigidly hold the die within the shell.

3. A button comprising a hollow shell and an integral hollow hub formed of relatively 60 65 soft metal, a hollow die of relatively hard

metal tightly fitting within the hub, a shoulder on said die overlying the peripheral edge of the hub, a cap on the button shell, the metal of the hub deformed at a plurality of points about the hub just below where the hub merges with the shell, complementary indentations in the die receiving the displaced metal of the hub to thus rigidly hold the die within the button shell.

4. A button comprising a hollow shell and an integral hub, a die fitting within said hub, the bottom of the die being radially split and perforate, the bottom of the hub of the button shell also being perforate, a shoulder on said die and overhanging the peripheral edge of the hub of the button shell, a cap on said shell and contacting with the upper surface of the die, and pointed indentations formed in the hub of the button shell and extending into the walls of the die 75 to rigidly secure the die in the button shell.

In testimony whereof we affix our signatures.

LEONARD R. CARLEY.
WALTER T. ABEL.
